Richard J. Cook
ATTORNEY

UNITED STATES PATENT OFFICE.

MYRON E. KENNEY, OF EVERETT, WASHINGTON.

CARPENTER'S PLANE.

Application filed October 15, 1923. Serial No. 668,563.

To all whom it may concern:

Be it known that I, MYRON E. KENNEY, a citizen of the United States, and a resident of Everett, Snohomish County, Washington, ⁵ have invented certain new and useful Improvements in Carpenters' Planes, of which the following is a specification.

This invention relates to improvements in carpenters' planes, and more particularly ¹⁰ to planes having two blades, one of which is set at an angle with respect to the other and to a transverse line transversely of the plane block.

Explanatory to the invention, it will be ¹⁵ stated that in certain kinds of mill work, as well as in general carpentry and cabinet work, it is frequently necessary to plane across the grain of the wood and into corners, or flush to an obstruction, and to my ²⁰ knowledge, there is no plane, of the two blade character, that is adapted to this class of work, therefore, it is the object of this invention to provide such a plane that is of simple and durable construction and ²⁵ which will serve all the purposes of the usual carpenter's plane as well as the special purpose above mentioned.

It is also an object of the invention to so ³⁰ design the body block, or frame of the plane, so that it can be cut or stamped from a single piece of metal and bent or shaped into form to carry the blades without the necessity of the addition of other parts for use as clamps or wedges.

Other objects reside in the details of construction and combination of parts as will ³⁵ hereinafter be described.

In accomplishing these objects I have provided the improved details of construction, ⁴⁰ the preferred forms of which are illustrated in the accompanying drawings, wherein—

Figure 1 is a side view of a two bladed plane constructed in accordance with the present invention.

Figure 2 is a top view of the same.

Figure 3 is a perspective view of the plane.

Referring more in detail to the drawings—

⁵⁰ 1 designates, in its entirety, the plane block, or body, which preferably would comprise a single piece of metal so cut and shaped as to provide a perfectly flat base plate 2 and a longitudinally extending side

flange 3 at right angles thereto. At the forward end of the frame is an inclined ⁵⁵ face 4 upon which a cutter blade 5 is mounted; said blade being provided on its back or under side with two parallel tongues 6 that are slidably dovetailed into grooves 7 in the face 4. A set screw 8 extends ⁶⁰ through a slot 9 in the blade and is threaded into the frame and may be tightened against the cutter to hold it at an adjusted position.

This blade is mounted at a right angle ⁶⁵ with respect to the flange 3 and is provided with the usual cutting edge 10. It is particularly adapted for planing close into corners or up to posts or other obstructions, and when not in use, may be removed or adjusted by loosening screw 8 so as to prevent its cutting edge from being damaged.

Rearwardly of the face 4 is another inclined face 12, set at an angle of approximately 45 degrees with respect to a line ⁷⁵ transversely of the block and also sloped at an angle of 45 degrees with respect to the base plate of the block. This face preferably is formed by cutting and turning up a part from the base.

Mounted on face 12 is a cutter 14 provided on its under face with two parallel tongues ⁸⁰ 15 that are dovetailed into grooves 16 in the supporting face. A set screw 17 extends through a slot 18 in the blade and into the ⁸⁵ face 12, and may be tightened against the blade to retain it at different positions of adjustment. The blade has a sharpened lower edge, as at 19, and the side flange 3 of the block is cut away as at 20 so as not to interfere with the turning away of the shavings when this cutter is used. This blade is used for planing across the grain of wood or on irregularly grained surfaces.

At its rearward end the frame is equipped ⁹⁵ with a handle 21 which may be formed as a part of the block, as illustrated, or attached thereto.

A plane so equipped with blades can be put to the various uses required of the carpenter's plane or rabbet plane and will be ¹⁰⁰ of value particularly in the fitting of windows.

Such planes it is apparent can be made in various sizes, and with frames of various ¹⁰⁵ types of construction other than here illus-

trated and for this reason I do not wish to be limited only to the details herein disclosed.

Having thus described my invention, what I claim as new herein and desire to secure by Letters-Patent, is:

A plane of the class described, formed from a single metal piece, comprising a floor base and a longitudinally extended side flange at right angles thereto, an inclined flange at the forward end thereof at right angles to the direction of movement of the plane and comprising means for ad-

justably sustaining a cutter blade in functional position, an inclined flange rearwardly of the forward flange disposed at an angle with respect to the movement of the plane and having means for adjustably sustaining a cutter blade in functional position and a rearward flange to form a handle for the plane. 15 20

Signed at Everett, Snohomish County, Washington this 21st day of September, 1925.

MYRON E. KENNEY.
